(57) **CLAIM**

The ornamental design for an enclosure for bathing area, as shown and described.

DESCRIPTION

In a preferred embodiment, the nature of this product is a plumbing fixture primarily useful for retaining water within a bathing area.

FIG. 1 is a right, top, front perspective view of an enclosure for bathing area embodying my new design;

FIG. 2 is a right side elevational view thereof, the front elevational view being a mirror image of the right side shown; and,

FIG. 3 is a top plan view thereof.

The broken line representations of a mounting environment in FIGS. 1-3, and of a drain in FIGS. 1 and 3, are for the purpose of illustration only, and form no part of the claimed design.
